(57) **CLAIM**

The ornamental design for milling machine for dental use as shown and described.

DESCRIPTION

1. Milling machine for dental use

1.1 : Perspective

1.2 : Perspective

1.3 : Front

1.4 : Back

1.5 : Left

1.6 : Right

1.7 : Top

1.8 : Bottom

Milling machine for dental use.

Elements shown in broken lines form no part of the claimed invention.
